UNITED STATES PATENT OFFICE

CARLYLE M. ASHLEY, OF ORANGE, NEW JERSEY, ASSIGNOR TO CARRIER ENGINEERING CORPORATION, OF NEWARK, NEW JERSEY

GAS TREATING DEVICE

Application filed April 9, 1928. Serial No. 268,467.

This invention relates to gas treating devices, and particularly to the treatment of such gases with a liquid preferably in the form of a fine spray. Such devices are particularly useful for conditioning air and for washing and scrubbing gases.

An object of this invention is to generally improve, render more efficient, and simplify gas treating devices.

10 Another object of the invention is to provide an improved gas treating device which is largely self-contained; which is to some extent portable; which may be made small and compact for use where a small capacity device is desired; which will be exceptionally efficient in action for all capacities for which it may be built; and with which the action of the liquid spray may be easily, effectively and conveniently controlled.

20 A further object of the invention is to provide an improved device for the treatment of a gas with which a more complete, perfect and uniform contact of the liquid and gas may be obtained under all operating conditions, and with which the escape of unvaporized moisture with the gas is effectively prevented.

A further object of the invention is to provide an improved device for treating gases, 30 which will require a minimum of lubrication; with which the treating liquid may be conditioned as to temperature and effectively utilized; which may be easily assembled; with which the bearings will be self alining; 35 which may be shipped without danger of injury to the bearings and other parts; and which will be relatively simple, compact, durable, light in weight, and inexpensive.

Various other objects and advantages will 40 be apparent from the following description of an embodiment of the invention, and the novel features will be particularly pointed out hereinafter in the appended claims.

In the accompanying drawings:

45 Fig. 1 is a sectional elevation of a device constructed in accordance with the invention;

Fig. 2 is a sectional elevation on a larger scale of some of the parts shown in Fig. 1;

50 Fig. 3 is a side elevation of the device;

Fig. 4 is a sectional plan of a portion of the same at the gas inlet opening, the section being taken approximately along the line 4—4 of Fig. 3;

Fig. 5 is a sectional elevation of the same, with the section taken along the line 5—5 of Fig. 3;

Fig. 6 is a sectional plan of the device, with the section taken approximately along the line 6—6 of Fig. 1;

Fig. 7 is another sectional plan of the same, with the section taken approximately along the line 7—7 of Fig. 1;

Fig. 8 is another sectional plan of the same, with the section taken approximately along the line 8—8 of Fig. 1;

Fig. 9 is another side elevation of the lower part of the device;

Fig. 10 is a sectional elevation of some of the parts of the liquid control;

Fig. 11 is a sectional plan of a portion of the liquid elevating conduit, the section being taken approximately along the line 11—11 of Fig. 2;

Fig. 12 is a diagram of the spray creating device, to illustrate its operation;

Fig. 13 is a diagrammatic plan of the casing and spray creating device of Fig. 12.

In the illustrated embodiment of the invention, the enclosing casing 10 may be of any suitable shape or size, but for example is illustrated as being square in cross section and of greater height than breadth. This casing may be formed of sheet metal and mounted upon any suitable base 11. The lower end of the casing is closed so as to serve as a reservoir 12, and immediately above the reservoir the casing is provided with a gas inlet opening 13 in one or more sides, as desired. The upper end of the casing is provided with one or more gas outlet openings 14 in one or more sides thereof, or an outlet opening may be provided in the top wall of the casing.

A skeleton frame 15 is provided upon the inside of the casing, which frame may be inserted or removed through the upper end of the casing, the top wall of the casing being removable for that purpose, and many of the movable parts of the mechanism for treat-

ing the gas may be mounted upon the skeleton frame. This skeleton frame may include a top frame section 16 and a bottom or base frame section 17, which are connected by a plurality of posts or standards such as at the corners of the frame sections. The upper frame section 16 may include a central pan or cup-shaped portion 18 connected to the outer band of the frame by a plurality of radiating arms 19, resembling very much the radial arms of a spider frame.

A source of power, such as an electric motor 20, is mounted in the cup-shaped portion 18 of the upper frame section 16, this motor having a depending driving shaft 21 (Fig. 2) which extends downwardly through the frame section 16. A fan or blower element 22 is provided with a hub 23 which fits over the depending end of the motor shaft 21, being secured thereon in any suitable manner, such as by a tapered pin 24 which is driven through the hub and an aperture in the shaft 21. The fan or blower element 22 includes a plurality of arms extending radially of the hub 23 and also a plate 25 which is secured to the hub and extends across the upper edges of the radial arms, so as to provide a closed or impervious upper end wall for the fan or blower element 22.

A spindle 26 is disposed below and aligned with the shaft 21 and enters the bore of the hub 23 of the blower element, being secured therein in any suitable manner, such as by another tapered pin 27 which may be driven transversely through the hub and adjacent end of the spindle. The spindle 26 may be reduced in diameter as at 26 for some distance below its point of connection to the hub 23, so as to be flexible, and below the flexible section the spindle is again relatively inflexible. The hub 23 is provided with a depending sleeve or shield portion 28 which extends along the flexible portion of the spindle 26 and to a point adjacent or below the lower end of the flexible portion, as shown in Fig. 2. The lower end of this sleeve 28 encircles the spindle 26 and is somewhat spaced therefrom, so that the spindle may have a small amount of clearance or lateral play therein to permit of a limited flexing of the flexible portion of the spindle 26.

A spray member 29 is secured to the lower end of the spindle 26 in any suitable manner, this member having, for example, a boss 30 which receives the lower end of the spindle 26 to which it may be coupled in any suitable manner, such as by a tapered or wedge pin 31 which may be driven through aligned, transverse passages in the boss and in the lower part of the spindle. This spray member 29 may be in the form of a shaft or conduit closed at its upper end and open at its lower end. The lower end of this spray member is rotatably mounted in a bearing ring 32 which is preferably formed of water lubri-

cated bushing materials such as lignum vitae, hard rubber, and graphite impregnated woods, the spray member extending somewhat below the bearing ring so as to open at its lower end below the bearing ring.

The lower frame section 17 of the frame 15 is provided with a plurality of arms 33, T-shape in cross section, which extend radially toward the vertical axis of the spray member and also upwardly in an inclined direction to some extent, these arms being connected at their inner ends by a ring 34. A somewhat cup-shaped flanged bearing member 35 is clamped or otherwise secured at its flange to the underside of this ring 34, such as by bolts 36 (Figs. 8 and 10). This bearing member 35 has a central tubular portion 37 depending from its flange and terminating at its lower end in an internal flange 38, and the bearing ring 32 is disposed within this depending portion 37 of the bearing member and rests upon the inturned flange 38.

Cushion means 39 may be disposed between the outer periphery of the ring 32 and the inner surface of the depending portion 37 of the bearing member 35, so as to permit of a limited lateral movement of the ring in order that the lower end of the spray member 29 may be somewhat self-aligning with respect to the motor shaft 21. This cushion means 39 may be one or more encircling rings of soft resilient rubber which yield to permit self-alignment of the bearing ring 32. The ring 32 is somewhat smaller in diameter than the cavity of the bearing member 35 in which it is placed, and the cushion means 39 not only permits limited lateral movement of the bearing ring, but also permits some axial tilting of the bearing ring as may be necessary for alignment of the lower end of the spray member with the motor shaft 21.

From the foregoing it will be observed that the spray member is suspended from the spindle 26, and the latter is in turn suspended from the boss of the fan or blower element 22 which is secured to the depending motor shaft 21. The motor thus suspends and rotates the blower element and the spray member, the flexibility of the spindle and the self-aligning bearing at the lower end of the spray member insuring free rotation of the blower element and spray member without binding. The sleeve 28 which guards the flexible portion of the spindle 26 prevents movements of the spindle to an extent which might cause injury thereto, and therefore the device may be shipped with safety and without danger of breakage of the spindle, due to blows or shocks to which it might be subjected while being transported.

A frustro-conical shield 40, Figs. 1 and 2, is disposed in an inverted position upon the upper face of the bearing member 35, and is provided at its lower or smaller end with an external flange by which it is secured to the

bearing member, such as by bolts or screws 41. The shield 40 extends above the liquid level maintained in the reservoir section of the lower end of the casing, which level is represented, for example, by the dash line 42 in Figs. 1 and 2. A stopper lever 43 is hinged by pivot pin 44 between depending ears 45 of the bearing member 35, and has an angular portion extending below the lower end of the bearing member 35 where it terminates in a stopper plate 46. This stopper plate is provided upon its upper face with an annular gasket 47 which may be held against lateral movement thereon by means of an annular ring 48 provided upon the upper face of the plate 46, which ring it surrounds or fits over, as shown clearly in Fig. 2. The stopper plate and its gasket engage with the lower end of the bearing member so as to close the opening in the same and thus control or prevent flow of liquid from the reservoir to the lower or open end of the spray member 29.

A lateral wall at the lower part of the casing 10 may be provided with a drawn out hump 49, Figs. 1, 3 and 8, and this hump extends upwardly above the liquid level in the reservoir part of the casing, being open at its upper end. The free end of the stopper lever 43 extends into this hump 49 where it is connected to the lower end of a rod or cable 50 which extends upwardly along the outer face of the casing 10 to a suitable operating arm 51 Fig. 3. This operating arm 51 may be manipulated manually if desired, but preferably is mechanically operated by a suitable motor device 52 which is controlled by circuit wires 53 leading to a suitable humidistat, not shown.

The spray member 29, adjacent its upper end, is provided with a plurality of radially extending pipes or tubular arms 54 which communicate at their inner ends with the interior passage 55 of the spray member 29 and at their outer ends terminate in discharge nozzles or spray-creating devices 56, which atomize the discharged liquid. Preferably the outer end of each arm or pipe 54 is bent laterally and horizontally so as to function as a hydraulic tourniquet. The nozzles 56 at the discharge ends of the arms or pipes 54 preferably discharge rearwardly of their direction of rotation with the spray member of which they form a part, and may also in some instances be given a slight downward tilt or inclination.

The frame 15 within the casing 10 is provided with a partition plate 57 above the spray member 29 and immediately below the fan or blower element 22, this partition or plate 57 extending toward the spindle 26 and having a central opening around the spindle which serves as a gas inlet leading to the center of the fan or blower element of the centrifugal type. The inner edge of the plate

57 along the central opening 58 may terminate in a small, upwardly oblique flange 58a. The fan may have a flange or lip 58b which depends into the opening 58 for the purpose of throwing back to a side of the machine any water which may be drawn along the bottom side of the plate 57 by air or gas currents in the casing. Thus, when the fan or blower element 22 rotates, it will draw gas upwardly through the central opening 58 in the partition 57 and discharge it outwardly towards the side walls of the casing. The partition prevents downward movement of this outwardly discharged gas, and consequently the gas will travel upwardly past the motor 20 and between the arms 19 of the upper frame section 16, while rotating horizontally to some extent.

Spray liquid is supplied to the reservoir 12 in any suitable manner, such as by a supply pipe 59 controlled by a suitable float-operated valve 60, so that the liquid level in said casing will be maintained substantially constant. Pipes 61 and 62 also connect the reservoir with any suitable liquid conditioning device, such as a cooling or refrigerating device (not shown), the liquid in the reservoir being withdrawn through the pipe 61, conditioned as to temperature and returned to the reservoir by the pipe 62. This circulation keeps the liquid in the reservoir at the desired temperature condition. The liquid may be withdrawn from the reservoir through a drain pipe 63 opening through the bottom wall of the casing. An overflow pipe 63a is threaded into the inlet end of pipe 63 in the bottom of the casing, and by unscrewing and removing the overflow pipe, the contents of the reservoir may be drained.

A steam supply pipe 64 may also be connected to the reservoir so as to extend into the reservoir for some distance, the portion within the reservoir having apertures 65 by which steam may be discharged into the reservoir for heating the liquid thereof. Such a steam pipe is a simple form of heater and may be used instead of the pipes 61 and 62 and the conditioning device in some instances where only heating is desired. For example, where the pipes 61 and 62 are connected to a refrigerating device, the use of the steam pipe 64 as a heater avoids the necessity of disconnecting the refrigerating device when for an interval it is desired to heat instead of refrigerate the spray liquid.

A cylindrical shell or wall 66 may closely surround the depending section 37 of the bearing member 35 and extend downwardly to the floor or bottom of the casing or reservoir (Figs. 1 and 2). This shell or wall 66 is provided with an aperture 67 through which the stopper lever 43 enters. The inlet pipe 62 preferably extends some distance into the reservoir towards the opening 67 and ter-

minates in proximity to but spaced from the opening 67. The spray liquid injected through the pipe 62 will thus be discharged in proximity to the opening 67 in a direction toward same, so as to tend to pass through the opening 67 and enter the enclosure formed by the shell or wall 66. Thus, when the stopper lever 43 is rocked to carry its plate 46 away from the bearing member 35, liquid will flow from the reservoir through the opening 67 into the enclosure formed by wall 66 and thence will pass upwardly into the open, lower end of the spray member 29.

The conditioned liquid entering the reservoir through the pipe 62 will largely pass into the enclosure and then into the spray member 29, with the result that the spray member will always receive the conditioned liquid before it has been materially modified by the other liquid remaining in the reservoir. Any excess of the conditioned liquid injected through the pipe 62 will of course pass into the reservoir, and if the injected supply is insufficient, other liquid from the reservoir will enter the enclosure through the opening 67.

The liquid which enters and rises in the lower end of the passage 55 of the spray member 29 will be rotated with the spray member, and elevated in the passage 55 to or above the level of the arms 54. The liquid will then move outwardly in the arms 54 by centrifugal action, and since these arms are rotating, they will exert a further centrifugal action on the liquid therein and discharge the same outwardly at considerable velocity, the discharged liquid being preferably discharged as a spray or in atomized form by reason of the nozzles 56.

To facilitate the elevation of the liquid in the passage 55, as in priming the device, the passage 55 may be made upwardly divergent, or of increasing or greater diameter for a portion of its length, and the lower part of this passage may also, if desired, be provided with one or more vanes, ribs or fins 68, which positively insure rotation of the liquid with the spray member, and hence serve as one form of priming means. These vanes or fins may be of any desired number and preferably extend from the lower open end upwardly for some distance. The liquid will rise in the bearing member 35 and the shield 40 to approximately the level of the surrounding liquid in the reservoir, and the immersion of the bearing ring 32 in this liquid will provide the desired lubrication for the lower end of the spray element.

In the illustrated embodiment of the invention, the spray member 29 is formed of a vertical tube having tubular arms extending laterally therefrom adjacent its upper end and terminating in discharge nozzles or terminals 56, but it will be observed that in principle the spray member may be con-

sidered as formed of a conduit having a vertical section opening at its lower end into the liquid of the reservoir, and one or more lateral sections terminating at their outer ends in discharge orifices 56a (Fig. 12). The vertical section of this conduit should have a portion of upwardly increasing cross section arranged or extending below the liquid level in said reservoir, in order to elevate liquid from the reservoir to the level of the lateral section. This upward increase in diameter or cross section may be abrupt, gradual, or both, or in one or more stages. Each lateral section of the conduit, is formed so as to swirl the column of liquid therein immediately preceding and approaching the orifice about an axis extending in the direction of liquid discharge from said orifice. In the illustrated embodiment of the invention, this swirl is obtained by introducing the column of liquid approximately tangentially into the casing of the discharge nozzle 56, in which case the discharge orifice 56a may be approximately central of a side wall of the nozzle casing.

The orifice is smaller than the inlet end of the lateral conduit section, and the lateral section of the conduit may, in some instances, also have a reduction in cross section intermediate its ends, and of a size intermediate the inlet end and discharge orifice. This reduction may also be gradual, abrupt, or both, or in one or more stages, one stage being illustrated in Fig. 12 at 54a. The liquid preferably is discharged backwardly with respect to the direction of travel of the discharge orifice during rotation of the spray member, and as discharged from such a device will have little or no momentum with respect to the casing, so that it will remain suspended as a finely divided or atomized spray or mist completely filling the interior of the casing including the central area thereof of which heretofore was not filled with spray from prior spray devices.

The liquid surrounding the lower end of the spray member, however, may tend to rise to some extent along the outer surface of the spray member, and to prevent this, the spray member at the same point above the liquid level in the reservoir and within the shield 40, Figs. 1 and 2, is provided with a laterally and outwardly extending surface 69 which throws off centrifugally, any liquid rising thereto along the outer surface of the spray member. This surface 69 may be provided in a simple manner by forming an annular bead on the periphery of the spray member, as illustrated in Figs. 1 and 2. The spray member may also be provided with an external annular ring 70 adjacent its lower end, which ring may be cut off to some extent at different points in order to balance the spray member and prevent vibration thereof during rotation.

When the stopper plate 46 is closed, the supply of spray liquid to the spray member will be cut off, and the liquid in the bearing member and shield will be drawn into the passage 55 of the spray member leaving the bearing ring 32 without sufficient liquid to lubricate it. To overcome this difficulty, the spray member may be provided with a small aperture 71 at a point above the ring 32 and below the upper limit of the shield 40, so that whenever the stopper plate 46 is closed, the last portion of the liquid which is drawn into the passage 55 will be partially discharged through the aperture 71. This discharged liquid falls upon the bearing ring to lubricate it, works through the ring along the spray member 29 to the lower end of the passage 55 and is again picked up and recirculated through the aperture 71. By this arrangement a small amount of liquid always will be continually recirculated through the aperture 71 in an amount sufficient to keep the bearing ring 32 wet and lubricated, whenever the stopper plate 46 is closed.

The gas inlet opening 13 is preferably somewhat below the spray arms 54, and thus the entering gas will have a maximum of contact with the spray discharged by the spray member. The slight downward tilt to the spray will be counter to the direction of flow of gas, and thus a more perfect, uniform and complete contact of spray and gas will be obtained, with less tendency for any unvaporized liquid to travel by inertia with the gas. Between the motor 20 and the gas outlet 14, a suitable liquid eliminator separator 72 may be arranged across the interior of the casing and through which the gas must pass in order to reach the outlets 14. This eliminator 72 may be supported upon the inside of the casing in any suitable manner, such as by brackets 73, and is preferably inclined somewhat in order to conduct to one side of the casing the unvaporized liquid separated thereby from the moving gas. This separated liquid will pass down one side of the casing to the reservoir without material contact with the gas column until after it has been recirculated and discharged through the spray member.

A heater element 74 may be disposed in the casing above the eliminator 72 in a position such that the gas leaving the eliminator 72 must pass through the heater element before reaching the outlets 14. The heater element may be of any suitable construction, such as by being formed of coils of pipes having spiral metal fins thereon for increasing the radiating surface. These coils may be supported in the casing in any suitable manner, such as by brackets 75, Fig. 1, and controlled by a valve 75a.

The upper edges of the radiating arms 19 of the upper frame section 16 are preferably downwardly hooked on similar sides as at 76,

so as to prevent disengagement of particles of unvaporized moisture from the side surfaces of these arms into the upwardly moving column of gas, these hooked edge portions 76 thus holding to the arms the unvaporized moisture engaging against the same as the gas passes upwardly between the arms. The gas leaving the blower element 22 will be circulating horizontally to some extent as well as passing upwardly, and the hooked edges are provided upon the faces of the arms 19 against which the gas impinges as it rotates. If desired, the upper edges of the other vertical surfaces of the upper section of the frame 15 may also have downwardly hooked portions 77 to also prevent the pulling from those surfaces by the moving gas of any unvaporized moisture which has collected thereon. The casing may also be provided with a sliding manhole or door 78, Fig. 1, through which access may be had to the motor for lubricating the same.

Each inlet opening 13 may have a slideable door 79, Figs. 3 to 5, cooperating therewith and by which the effective opening may be varied, so that the quantity of gas entering the casing may be varied to some extent. This door may be slidably confined against the casing walls by suitable guide flanges 80 having grooves facing one another along the opposite side edges of the opening, and each door may have a suitable handle 81 by which it may be raised or lowered, as desired. The door 79 shown in Figs. 3-5 is indicated by full lines in its closed position and by dash lines in a partially open position. While normally the ingoing gas will be sufficient to prevent the exit of spray through the inlet openings, I preferably provide louvre plates 82 across each inlet opening 13. These louvre plates may be V-shaped and arranged vertically in spaced but somewhat nesting relation to one another, as shown in Fig. 4, but sufficiently close to one another to compel gas or spray to travel in a circuitous path from one face to another of the row of louvre plates. These plates 82 may have their outer edges hooked rearwardly and inwardly of the V as at 83, to trap any spray moving outwardly along the surfaces of these plates.

The plates 82 may extend between and be connected to upper and lower plates 84 and 85 which have flanges 86 along their forward edges hooked over the upper ends of the plates 82 to confine them together. The upper and lower ends of the plates 82 may also have angular flanges 87 fitting flatwise against and secured to the upper and lower plates 84 and 85. These angular flanges 87 also serve as spacers between the plates 82 during assembly. The upper and lower plates 84 and 85 are also provided with laterally extending angular portions or flanges 88 which are slidably guided in the grooves of the guide flanges 80 adjacent the door 79, so that the

louvre plates across each inlet 13 may be raised or lowered as a group when access to the interior of the casing through any inlet opening 13 is desired.

In the use of a gas treating device constructed as herein described and illustrated, the reservoir is filled to a desired level with a spray liquid, such as to the level indicated by the dash line 42, in Figs. 1 and 2. Assuming that the gas to be treated is air and that the air is to be dehumidified, the pipes 61 and 62 will be connected to a refrigerating device, so that the liquid in the reservoir will be circulated through the refrigerating device 10 repeatedly and returned to the reservoir at a point adjacent the opening 67. Further assuming that the relative humidity of the air is too high, the humidistat, not shown, will have operated the motor 52 to set the arm 51 in a position in which it elevates the outer end of the stopper lever 43 and moves the stopper plate 46 away from the bearing member 35, so that the liquid within the enclosure formed by the wall 66 can flow around the outer edge 20 of the stopper plate to the lower open end of the passage 55 of the spray member 29.

The motor 20 is started and the blower element 22 and spray member 29 will be rotated by the motor. The blower element 22 induces 30 an upward movement of air through the casing, and the liquid entering the lower end of the spray element will be rotated thereby, raised to the level of the pipe arms 54 and then discharged in the form of a spray very 35 much in the manner of discharge from a hydraulic tourniquet, with the exception that the arms of the tourniquet in this device are motor driven in a direction opposite to the direction in which the discharge of the spray 40 occurs. With backwardly directed but power driven spray nozzles, a more complete, efficient and uniform contact of the liquid and air is obtained, due probably to the fact that by separately driving the tourniquet, the 45 fine spray discharged by the nozzles will have little momentum relative to the casing when discharged, and only the heavier or unvaporized particles will be thrown outwardly against the walls of the casing, the discharged 50 liquid largely remaining distributed throughout the interior of the casing in the form of a suspended fine mist for contact with the air column.

By disposing the nozzles slightly above the 55 opening inlets 13, there will be less tendency for any unvaporized moisture to escape through the inlet openings 13, and the slight downward inclination of the spray will be counter to the direction of travel of the air, 60 which has been found to aid the mixing of the air and the spray mist. The backward discharge of the spray liquid tends to lessen the resistance to rotation of the spray member, and hence less power is required to rotate 65 such a spray member than would be necessary

if the nozzles discharged forwardly of their direction of travel during rotation.

By this backward discharge of the nozzles, the discharged liquid will have little momentum when discharged as a fine spray or mist and therefore the mist will remain largely in suspension in the air column, and only the heavier particles discharged by the nozzles will have sufficient inertia to be thrown outwardly to the sides of the casing 70 beyond the limits of the air column which is drawn towards the center by the central opening 58. Some or all of the nozzles may also discharge the liquid with a slight lateral inclination toward their axis of rotation so as 75 to provide spray in the center of the casing as well as along the sides.

The blower element being of the centrifugal type further mixes the air and liquid handled thereby, and by producing a sharp 80 change in the direction of travel of the air and liquid, any unvaporized liquid will impinge against the blades of the blower element and be brought, while adherent, in contact with further air which strikes the blades 85 of the blower element. The liquid particles thrown off from the blades of the fan will be broken up into a fine mist for contact with the swirling gas. If an excess of unvaporized liquid collects on the blower element, it 90 will be thrown outwardly by centrifugal action against the sides of the casing and will then run down the sides to the reservoir for recirculation through the spray. The radiating arms and the hooks 77 on the upper 95 frame section 16 will further aid in removing unvaporized moisture from the air, and the eliminator 72 will complete the elimination 100 from the passing air of any unvaporized moisture. If it is desired to elevate the temperature of the dehumidified air, this can be 105 done by conducting a heating fluid through the coils 74.

The amount of air passing through the casing can be varied by sliding upwardly and 110 downwardly the doors 79 at the inlet openings 13. By operation of the motor 52 under either manual or automatic control, the stopper lever 43 may be rocked to move the stopper plate 46 into partial or entire obstructing position against the bottom of the bearing member 35 so as to cut down or off 115 the amount of liquid entering and discharged by the spray member 29. During rotation of the spray member, the circulating liquid will keep the bearing ring 32 lubricated whether or not the stopper plate is closed, and the bearing for the lower end of the spray member is self-aligned, this self-alignment being 120 permitted by the flexibility in the spindle 26 and the limited self-adjustment of the bearing ring 32. On the other hand, there is no danger of breakage of the rotary parts in 125 shipping the device because of the protection 130

afforded for the flexible portion of the spindle.

The invention has been described in connection with an embodiment which has been found useful in the conditioning of air, but it will be understood that devices constructed in accordance with this invention can also be advantageously used in the treatment of various gases by various liquids. It will also be obvious that various changes in the details, which have been herein described and illustrated in order to explain the nature of the invention may be made by those skilled in the art within the principle and scope of the invention as expressed in the appended claims.

I claim as my invention:

1. A gas treating device comprising a driving element rotatable about a vertical axis, a spray member arranged in alinement with the lower end of said element and at its upper end secured to said element for rotation therewith, said member below its connection to said element having a portion of relatively small diameter to permit flexing thereof, said element having a guard encircling said member at a point adjacent to or below said flexible portion and having some clearance therewith to permit a limited lateral movement of said member while flexing, said member having therein a passage, a floating bearing for the lower end of said member, means for supplying a liquid to the passage in said member, and a spray device carried by said member and communicating with the passage thereof for discharging a liquid from said member while the latter is rotating.

2. A gas treating device comprising a vertically extending shaft having a passage opening through its lower end and extending upwardly therein for some distance, a spray creating device carried by said shaft above its lower end and communicating with said passage to receive therefrom a liquid to be discharged, means for rotating said shaft, a liquid reservoir into which the lower end of said shaft extends whereby liquid may enter the lower end of said shaft and be elevated and discharged as a spray, a bearing for said shaft adjacent its lower end, through which the shaft and its passage extend, and including a shield portion extending around the bearing and above the liquid level in said reservoir, and a stopper device adjustably cooperating with said bearing to control liquid flow into said shaft from said reservoir.

3. A gas treating device comprising a vertically extending shaft having a passage opening through its lower end and extending upwardly therein for some distance, a spray creating device carried by said shaft above its lower end and communicating with said passage to receive therefrom a liquid to be discharged, means for rotating said shaft, a

liquid reservoir into which the lower end of said shaft extends whereby liquid may enter the lower end of said shaft and be elevated and discharged as a spray, a bearing for the lower end of said shaft having a portion extending above the liquid level in said reservoir and open at its lower end, and a stopper device movable into and out of a position in which it closes the opening in the lower end of said bearing to control the liquid flow to said shaft from said reservoir.

4. A gas treating device comprising a vertically disposed tubular conduit, means for rotating said conduit about a vertical axis, said conduit being open at its lower end, a liquid reservoir into the liquid of which said lower end of said conduit extends, a spray device carried by said conduit and discharging liquid elevated in said conduit, a ring of water lubricated material having a bearing passage into which the lower end of said conduit extends and in which said conduit rotates, said conduit having a small lateral opening above said ring to discharge thereon a small stream of liquid elevated in said conduit by rotation of the latter, whereby sufficient of the elevated liquid will be discharged upon said ring to lubricate the same.

5. A gas treating device comprising a casing having an apertured partition intermediate its ends, a blower in said casing arranged adjacent one face of said partition and across the aperture thereof, and also having a flange extending into said aperture and adjacent the edge thereof, a spray creating device in said casing at the side of said partition opposite said blower, said casing having a gas inlet therein for conducting a gas to be treated to said spray creating device, and also a gas outlet at the blower side of said partition, whereby said gas will be conducted through said casing in contact with said spray, the flange on said blower throwing back toward the casing walls any unvaporized liquid which may be drawn along the face of said partition opposite said blower by the current of gas passing through the aperture of said partition.

6. A gas treating device comprising a liquid reservoir, a spray member having a tubular portion depending into and opening into said reservoir, and also having spray creating means communicating with said tubular portion to receive liquid therefrom, and driving means having a suspension connection to said spray member which is of greater flexibility than said member for suspending and rotating the spray member.

7. A gas treating device comprising a liquid reservoir, a conduit having an approximately vertical and a lateral section, said vertical section having its lower end opening into the liquid in said reservoir, said conduit being rotatable about the vertical axis of its vertical section and the outer

- free end of the lateral section having a discharge orifice, said vertical section below the liquid level in said reservoir, increasing in cross section upwardly, and the orifice of said lateral section being smaller than the 5 inlet end of the lateral section, said lateral section being formed to swirl the liquid immediately preceding and approaching said orifice about an axis extending in the direction of discharge through said orifice, where- 10 by the liquid in the reservoir will by rotation of said conduit be elevated through the vertical section into the lateral section and discharged from the latter through said orifice.
- 15 8. A gas treating device, comprising a vertically disposed conduit, freely flexible means for suspending said conduit and rotating the same upon a vertical axis, said conduit provided with means for admitting a liquid to 20 the lower part thereof and causing it to be sprayed from its upper portion, a motor for causing the suspended conduit to be rotated at its upper end, and laterally yieldable means about the conduit at its lower end to 25 maintain the rotating conduit in dynamic balance.
9. In a gas treating device, the combination of a vertical tubular member provided at 30 the bottom with an inlet and at the top with spraying devices, a liquid reservoir into which the lower end of the tubular member extends for receiving liquid therefrom, means connected to one end of said member for rotating the tubular member about its vertical 35 axis, and yielding bearing means for the upper and lower portions of the tubular member which permit lateral movement of the member whereby during rotation thereof the tubular member may have freedom for automatic 40 adjustment of its bearing means.
10. A gas treating device comprising a closed, vertically extending conduit open at its lower end, a reservoir into which the 45 lower end of said conduit extends, means for rotating said conduit about its vertical axis, said conduit having a closed tubular arm communicating with the upper end of the conduit and rotating therewith, said tubular 50 arm extending outwardly in a somewhat radial direction from said conduit and terminating at its outer end in a fine spray producing orifice discharging rearwardly with respect to its direction of rotation, and normal to a radius from said orifice to said axis, whereby said discharged spray will be substantially free of momentum in said casing and the propelling force of the discharged liquid will aid the rotation of said conduit to 55 elevate additional liquid.
- 60 11. A gas treating device comprising a closed, vertically extending conduit open at its lower end, a reservoir into which the lower end of said conduit extends, means for rotating said conduit about its vertical axis, said conduit having a closed tubular arm communicating with the upper end of the conduit and rotating therewith, said tubular arm extending outwardly in a somewhat radial direction from said conduit and terminating at its outer end in a fine spray producing orifice discharging rearwardly with respect to the direction of rotation of the chamber about the vertical axis of said conduit, whereby liquid will be elevated, and then discharged as a fine mist 70 without substantial momentum, and means for passing a current of gas through the space in which said mist is created.
12. A gas treating device comprising a rotating member, a closed tubular arm carried by said member and extending laterally away from the axis of said member, means for rotating said member about said axis, means for supplying a liquid to the inner end of said arm for discharge through said arm by centrifugal action, the outer end of said arm terminating in a cylindrical, disc-like chamber into which the passage of said arm enters in a direction somewhat tangentially of the outer portion of the chamber, whereby the liquid entering the chamber will be whirled spirally and inwardly, one end of said chamber having a short, approximately central orifice through which the whirling liquid of the chamber is discharged, said chamber being disposed with said orifice discharging rearwardly with respect to its direction of travel while rotating with said chamber, whereby the liquid discharged will be in the form of a fine mist and in suspension and substantially motionless in the space into which it is discharged, and means for passing a current of gas through said space for contact with said mist.
13. A gas treating device, comprising a casing having a gas inlet opening in one part thereof and a gas outlet opening in another part thereof, a motor mounted in said casing between said inlet and outlet openings and having a shaft, a blower element and a rotary spray device carried and rotated by said shaft between said inlet and outlet openings, with the blower and motor between the spray device and the outlet, means for supplying liquid to said spray device during its rotation, a partition in said casing between the spray device and the blower element and having an opening for conducting a gas from the space around the spray device to the intake side of the blower, the blower element discharging the gas into the part of the casing toward said outlet, and a free moisture eliminator disposed between said outlet and said blower and motor through which the gas must pass in reaching said outlet.

14. A gas treating device comprising a casing, means for passing a current of a gas to be treated through said casing, a nozzle of a type which atomizes into a misty condition, any liquid discharged by it, means supporting said nozzle for rotation in said casing and in a path well spaced from the wall of said casing, means for supplying a treating liquid to said nozzle during its rotation, and mechanical means for rotating said nozzle in a direction opposite from the direction of discharge of liquid from said nozzle, said casing having no obstructions between its wall and said rotating nozzle. 70
15. A gas treating device comprising a casing, means for passing a current of a gas to be treated through said casing, a nozzle of a type which atomizes into a misty condition, any liquid discharged by it, means supporting said nozzle for rotation in said casing and in a path well spaced from the wall of said casing, means for supplying a treating liquid to said nozzle during its rotation, and mechanical means for rotating said nozzle in a direction opposite from the direction of discharge of liquid from said nozzle, said casing having no obstructions between its wall and said rotating nozzle, said nozzle discharging its liquid in a direction substantially normal to a radius from the nozzle discharge opening to the axis of rotation of said nozzle, whereby the liquid when discharged will be left substantially in motionless suspension in said casing. 75
16. A gas treating device comprising a casing, means for passing a current of a gas to be treated through said casing, a rotary member having a substantially closed vertical passage along the axis of rotation of said member and also a laterally extending substantially closed passage connected to the upper end of said vertical passage, mechanical means for rotating said member, said lateral passage discharging any liquid therein in a direction rearwardly of the direction of movement of the discharge end and substantially normal to the radius from said discharge end to said axis, means for supplying liquid to the lower end of said vertical passage, said vertical passage having therein means operable by rotation of said member to elevate the liquid supplied to said vertical passage and deliver it to the inner end of said lateral passage, said discharge end being spaced well from said casing and said axis, and said casing being free of obstructions between said axis and discharge end in the section adjacent said end, whereby liquid discharged by rotation of said member will be substantially motionless in said casing at the instant following discharge, and the propelling force of the discharged liquid will aid in the power required to rotate said member and elevate said liquid therein. 80
17. The method of treating a gas with a liquid which comprises positively whirling a confined angular column of liquid about an axis approximately coincident with the longitudinal axis of one arm of the column, elevating the column in the axial arm by the whirling, and discharging the liquid from the free end of the other arm of the column in a direction rearwardly of the direction of rotation at that end and normal to a radius from the discharge end; whereby the reactive propelling force of the discharged liquid will provide part of the rotating force which elevates the liquid in the axial arm of the column; and passing a gas to be treated through the path of the discharge end of said column. 85
18. The method of treating a gas which comprises rotating a column of liquid about an axis adjacent one end of the column and transverse to the axis of the column end nearest thereto, so as to create a centrifugal pressure on said column tending to discharge the liquid thereof from free end of the column, restricting the cross sectional area of said column at a plurality of stages toward the discharge end of the column, with the smallest cross sectional area at the discharge end of the column. 90
19. The method of treating a gas with a liquid which comprises whirling a column of liquid rapidly about an axis adjacent one end of the column and extending crosswise of the axis of the adjacent end of the column, so as to urge movement of said column along its axis by centrifugal force, and discharging the liquid of said column from the outer end of the column in a direction opposite from the direction of travel of the discharge end of the column and substantially normal to a radius from the discharge end of said column to said axis of rotation, whereby the discharged liquid will be substantially motionless and free of momentum an instant after its discharge from said column. 95
20. A gas treating device comprising a shaft, means for rotating said shaft about its axis, a hydraulic tourniquet device connected to and rotatable with said shaft and discharging liquid therefrom in a direction reverse to the direction of rotation of said shaft, and substantially normal to a radius from the discharge opening to the axis of rotation, said device discharging through a nozzle having a relatively small opening designed to build up a pressure within the device, and means for supplying a liquid to said tourniquet device while rotating with said shaft. 105
